UNITED STATES PATENT OFFICE.

JOHN L. DAWES, OF PITTSBURG, PENNSYLVANIA.

DESIGN FOR A BOTTLE.

SPECIFICATION forming part of Design No. 24,333, dated May 28, 1895.

Application filed December 22, 1894. Serial No. 532,726. Term of patent 14 years.

To all whom it may concern:

Be it known that I, JOHN L. DAWES, a resident of Pittsburgh, in the county of Allegheny and State of Pennsylvania, have invented and 5 produced a new and original Design for Bottles, reference being had to the accompanying drawings, forming part thereof, in which—

Figure 1 is a front elevation of a bottle embodying the design. Fig. 2 is a side elevation 10 of the same. Fig. 3 is a top view of the same. Fig. 4 is a horizontal section on the line 4 4, Fig. 3.

The leading features of my design consist in a bottle, without a neck, having a round 15 or circular body portion, a flange around the top of the bottle, a spout on the side of the bottle, and a recess formed on the front of the bottle in the body portion.

A represents the body portion of the bottle, having the recess b therein. c represents the 20 flange, which extends around the top of the bottle. At one side of the bottle is the spout d, said spout extending out from the flange c and body portion a at the top of the bottle.

I claim—

The design for bottles, substantially as herein shown, and described.

In testimony whereof I, the said JOHN L. DAWES, have hereunto set my hand.

JOHN L. DAWES.

Witnesses:

J. N. COOKE,
W. J. GRIBBEN.
